United States Patent

Des. 242,533
Patented Nov. 30, 1976

242,533

ELECTRONIC THERMOMETER CASE

George H. Schmidt, Douglaston, N.Y., assignor to
Arbrook, Inc., Arlington, Tex.

Filed June 10, 1975, Ser. No. 585,556

Term of patent 14 years

Int. Cl. D10—04

U.S. Cl. D10—60

FIG. 1 is a front elevational view of an electronic thermometer case showing my new design;

FIG. 2 is a right side elevational view thereof;

FIG. 3 is a left side elevational view thereof;

FIG. 4 is a top plan view thereof;

FIG. 5 is a bottom plan view thereof.

I claim:

The ornamental design for an electronic thermometer case, substantially as shown and described.
